UNITED STATES PATENT OFFICE

2,517,254

CAMP HEATING AND COOKING STOVE

Charles T. Steele, Ecorse, Mich.

Application April 18, 1947, Serial No. 742,237

2 Claims. (Cl. 126—93)

1

The invention relates to a combination heating and cooking stove especially adapted for fishermen, hunters and campers and is arranged to provide a heated seat or stool which the user may occupy when fishing through the ice or the like.

The invention has for its object the provision of a collapsible stove formed of two telescoping, hollow, cylindrical members with means for holding the same in extended position when it is desired to use the stove as a seat or stool and means for collapsing the stove to transport or store the same.

Another object is to provide such a stove formed of two cylindrical receptacles, the lower receptacle being closed at its lower end and open at its top, while the upper receptacle is closed at its upper end and open at its lower end so as to telescopically receive the lower receptacle therein.

A further object is to provide a stove of this character in which a wood top or seat is formed upon the top of the upper member and spaced therefrom by a layer of asbestos.

A still further object is to provide a collapsible stove of the character referred to in which spring loaded lugs are carried by the upper member and adapted to selectively engage openings near opposite ends of the lower member for holding the device in extended or closed condition as desired.

It is also an object of the invention to provide a handle bale upon the upper member so that the stove may be easily transported.

A further object is to provide a stove of this character in which a contractible release band is carried upon the upper member for withdrawing the spring loaded lugs from the openings in the lower member when it is desired to change the adjustment.

Another object is to provide a heater of this character in which the spring loaded stop lugs are mounted upon the U-shape spring members connected to the top of the upper member, the lugs being slidably movable within channel guides mounted in the lower member.

Still another object is to provide a stove of this character having a cooking plate removably mounted within the upper portion of the lower member whereby the upper member may be entirely removed when it is desired to use the stove for a cooking stove.

The above objects together with others which will be apparent from the drawing and following description, or which may be later referred to,

2

may be attained by constructing the improved collapsible stove in the manner hereinafter described in detail and illustrated in the accompanying drawing, in which:

Figure 1 is a vertical longitudinal sectional view through the stove in extended position;

Fig. 2 a perspective view of the stove in collapsed position;

Fig. 3 a side elevation of the stove in collapsed position;

Fig. 4 a vertical longitudinal section through the stove in closed position; and,

Fig. 5 a section on the line 5—5, Fig. 4.

The stove comprises generally two hollow cylindrical members in the form of receptacles having their open ends telescopically engaged. The lower member, indicated generally at 10, comprises the cylindrical side walls 11 and the flat bottom wall 12 and the upper member, indicated generally at 13, comprises the cylindrical side walls 14 of sufficiently greater diameter to slidably receive the cylindrical side walls of the lower member, and the flat top wall 15.

Both of these members may be formed of sheet metal of suitable gauge to provide sufficient strength to hold the weight of a person when the stove is used as a heated seat or stool by a fisherman or hunter in cold weather.

For this purpose a wood seat or cover, as indicated at 16, is fixed upon the top of the upper member, an asbestos layer 17 being located between the same and the flat top wall 15 of the upper member.

A pair of U-shape spring members 18, preferably located at right angles to each other, are connected to the inside of the flat top wall 15 of the upper member, and the legs of these U-shape members extended down within the side walls 14 of the upper member and have stop lugs 19 welded or otherwise rigidly connected to their lower ends and arranged to project through apertures 20 in the lower portion of the cylindrical side walls 14 of the upper member.

A handle bale 21 may be pivotally connected to the brackets 22 which are welded or otherwise attached to the upper portion of the side walls 14 of the upper member to provide means for easily carrying the stove when not in use.

A multiplicity of vent openings 23 may be located around the upper portion of the side walls 14 of the upper member, providing a vent for the products of combustion.

Vertically disposed channel guides 24 are welded or otherwise connected to the side walls 14 of the lower member at four equally spaced

points so as to provide guides within which the legs of the spring members 18 and stop lugs 19 may slidably move.

Apertures 25 and 26 are provided in the upper and lower portions respectively of the channel guides 24 and cylindrical side walls 11 of the lower member to permit selective engagement of the stop lugs 19 therewith for holding the stove in either extended or collapsed condition as shown in Figs. 1 and 4.

For the purpose of withdrawing the stop lugs 19 from the apertures, a release band 27 is provided. This band may be formed of sheet steel with sufficient spring therein to cause it to normally assume the open position best shown in Fig. 5.

Channel clips 28 may be welded or otherwise rigidly attached to the exterior of the lower portion of the cylindrical side walls 14 of the outer member in a horizontal plane coinciding with the openings 20 therein, the release band 27 being slidably received within these channel clips and having its opposite ends rolled as indicated at 29, or other projections formed thereon, to provide finger grips so that with the thumb and fore finger engaging the two projections 29 the ends of the release band may be drawn towards each other collapsing the band and forcing the stop lugs 19 inward so that their outer rounded ends are flush with the outer surface of the cylindrical side walls 14 of the upper member whereby a vertical movement of the upper and lower members relative to each other will be permitted.

Any conventional small oil heater or lamp, as indicated in broken lines at 30 in Fig. 1, may be placed in the lower portion of the lower member 10 to provide the necessary heat within the stove.

With the stove in extended position as shown in Fig. 1, it may be used as a heated seat or stool upon which a fisherman or hunter may sit to keep warm, as when fishing through the ice.

When it is desired to collapse the stove so that it may be carried from one place to another, the release band may be collapsed in the manner above described forcing the stop lugs 19 inward so that by relative longitudinal movement of the lower and upper members 10 and 13, the rounded outer ends of the stop lugs will be caused to move out of the upper apertures 25 on the lower member whereby the two members may be collapsed to the point where the lugs 19 will engage the lower apertures 26 in the lower member holding the two members in collapsed position as shown in Figs. 2, 3 and 4 so that it may be easily picked up and carried by means of the bale 21.

The stove may also be used as a cooking stove and for this purpose a cooking plate 31 is provided in the form of a sheet metal disc having peripheral notches 32 to accommodate the channel guides 24 and preferably having the large central opening 33 which may be surrounded by a plurality of radial ribs 34.

When used as a cooking stove the upper member 13 may be entirely removed from the lower member and any suitable cooking utensil may be placed upon the cooking plate.

I claim:

1. A stove of the character described comprising

ing a lower receptacle comprising a bottom wall and side walls, an inverted upper receptacle telescopically mounted upon the lower receptacle and comprising a top wall and side walls, inverted U-shape spring members connected to the under side of the top wall of the upper receptacle, the legs of said U-shape spring members depending within the side walls of the receptacles, out-turned lugs connected to the lower ends of said legs adjacent to the lower end of the upper receptacle, there being apertures in the lower portions of the side walls of the upper receptacle receiving said lugs and upper and lower series of apertures in the side walls of the lower receptacle for selectively receiving said lugs for locking the stove in extended or collapsed condition, U-shape guide clips on the exterior of the side walls of the upper receptacle near the lower edge thereof, and a split release ring located in said guide clips and surrounding the ends of said lugs for withdrawing the lugs from said apertures.

2. A stove of the character described comprising a lower receptacle comprising a bottom wall and side walls, an inverted upper receptacle telescopically mounted upon the lower receptacle and comprising a top wall and side walls, inverted U-shape spring members connected to the under side of the top wall of the upper receptacle, the legs of said U-shape spring members depending within the side walls of the receptacles, out-turned lugs connected to the lower ends of said legs adjacent to the lower end of the upper receptacle, there being apertures in the lower portions of the side walls of the upper receptacle receiving said lugs and upper and lower series of apertures in the side walls of the lower receptacle for selectively receiving said lugs for locking the stove in extended or collapsed condition, U-shape guide clips on the exterior of the side walls of the upper receptacle near the lower edge thereof, a split release ring located in said guide clips and surrounding the ends of said lugs for withdrawing the lugs from said apertures, and vertical channel guide members fixed to the interior of the side walls of the lower receptacle for guiding said spring legs and lugs.
